J. R. TULLY

PUSH ROD SILENCING DEVICE FOR INTERNAL COMBUSTION MOTORS

Filed May 28, 1921

FIG. 1

Inventor
James R. Tully

By

John Allen

AT&T

UNITED STATES PATENT OFFICE.

JAMES R. TULLY, OF HUNTINGDON, QUEBEC, CANADA.

PUSH-ROD-SILENCING DEVICE FOR INTERNAL-COMBUSTION MOTORS.

Application filed May 28, 1921. Serial No. 473,388.

To all whom it may concern:

Be it known that I, JAMES R. TULLY, a subject of the King of Great Britain, and resident of the town of Huntingdon, in the 5 Province of Quebec and Dominion of Canada, have invented certain new and useful Improvements in Push-Rod-Silencing Devices for Internal-Combustion Motors, of which the following is a full, clear, and exact 10 description of the invention.

This invention relates to improvements in push rod silencing devices for internal combustion motors, and the object of the invention is to provide a simple, durable, inexpensive and efficient means for eliminating the clicking which is inherent to the push rods of internal combustion motors.

A further object is to improve the lubrication of the tappets.

20 A still further object is to eliminate wear of the push rods and tappets where they meet.

Internal combustion engines of the four cycle type, as at present generally used for 25 automobile and marine work, all employ loose push rods between the tappets and valve stems or rockers, according to whether the engine is valve in the cylinder or valve in the head type. There is necessarily a 30 slight slackness or clearance between these push rods and the tappets and valves or rockers to permit the valves to close tightly, especially when the engine is well heated up and the valve stems, push rods and tappets 35 have expanded. This necessary clearance causes a very noticeable clicking as the parts come together and when the engine is running at high speed the clicking develops into a considerable and disagreeable sound. Fur-

40 thermore, each click indicates a not inconsiderable hammer blow and such blows frequently repeated wear the push rods, tappets and valve stems or rockers so that the clearance is increased and the condition ag- 45 gravated. This is especially so when the engine is operating in a dusty atmosphere from which grit settles on the parts and works between the abutting faces of the parts.

50 According to the present invention, this clicking noise is entirely eliminated and wear due to grit done away with by providing a dust-tight, oil-filled casing around the ends of the push rods. The push rods are 55 usually disposed vertically with the tappets beneath them and in most cases it will suffice

to enclose the lower ends of the push rods and upper ends of the tappets.

In the drawings which illustrate the invention:—

60 Fig. 1 is a vertical sectional view of a tappet guide formed according to the invention.

Fig. 2 is a vertical sectional view illustrating the invention applied to an existing 65 tappet guide.

Referring more particularly to the drawings, 11 designates a tappet guide, 12 a tappet and 13 a push rod of any design.

According to this invention a casing 14 is 70 provided above the guide 11, either integral therewith as shown in Figure 1 or separate therefrom as shown in Figure 2. This casing surrounds the lower portion of the push

rod in spaced relation thereto and serves to hold a heavy oil, such as is generally known 75 as "cylinder oil," indicated at 15. To hold the oil against escape at the top of the casing and also to exclude dust, a cap 16 is attached to the top of the casing, preferably

80 by screw threads. The cap preferably contains a felt washer 17 which it holds down against the top of the casing, thus keeping the washer in place. The felt washer may be supported from below by a rigid washer 18 resting directly on the casing. Preferably

85 the push rod is a tight fit in the felt washer so that oil will not work up on the rod nor dust work down. The felt washer is kept wet with oil from within the casing adhering to the push rod and is thus self-lubricat-

90 ing. The cap and metal washer 18 have apertures 19 for the passage of the push rod, considerably larger than the rod, so that the rod will not touch them. In this way the alignment of the tappet rod and valve stem 95

or rocker is not interfered with, the felt washer being sufficiently yielding to permit any lateral movement of the rod.

100 In an engine of the valve in the head type where rockers are used, the push rods are generally connected to the rockers so that the push rods hang from the rockers and the clearance is formed between the push rod and tappets. For an engine of this type the device as thus far described is 105 complete. In an engine of the T-head or L-head type where the valves are inverted and their stems depend in alignment with the push rods, it will usually be found that the push rods are free from the valve stems 110 and it follows that by the action of gravity the push rods will rest on the tappets

and the clearance will be formed between the push rods and valve stems. As the clicking occurs when the clearance is closed up and as it is not convenient to provide 5 casings as described about the lower ends of valve stems it is necessary to transfer the clearance from the upper to the lower ends of the push rods. This may be easily accomplished by providing a light spring 20 10 in compression between the cap 16 and a collar 21 mounted on the push rod. This spring need be only strong enough to hold the push rod against the valve stem and maintain the clearance at the lower end of 15 the rod.

In operation the device is as follows:— The heavy oil in the casing forms a cushion between the tappet and push rod. The oil being heavy will not easily squeeze out from 20 between the parts, especially where the push rod loosely enters the tappet or vice versa. The oil compels the parts to come together gently and thus the clicking sound is entirely eliminated. The felt washer keeps 25 the oil from escaping from the casing or creeping up on the push rod and also excludes dust and grit thus reducing the wear of the parts. The oil in the casing serves also to lubricate the tappet and if the oil is 30 of sufficient body it will escape only very slowly between the tappet and guide and until nearly or completely exhausted is available for cushioning purposes. Escape 35 of oil through this channel is no disadvantage as it runs into the engine base. Preferably the casing should be nearly full of oil when the tappet is in its uppermost position, as indicated in Figure 1, therefore care should be taken when filling the casings to note the position of the tappets and 40 gauge the proper oil level accordingly.

As indicated in the drawings the invention is applicable either by providing new tappet guides or by attaching the oil casing 45 to an existing guide. While it is obviously preferable to locate the device at the lower

ends of push rods, it will be understood that it may be located at the upper ends of the push rods or applied to similar mechanisms without departing from the spirit of the 50 invention. It will also be understood that the invention is not limited to any particular style or design of tappet guide, tappet and push rod but applies equally to all. It will furthermore be understood that the 55 form of casing shown and described is merely for illustration and that the invention is not limited thereto but embraces all such special forms of construction as may be necessary to accommodate it to engines 60 of different designs.

Having thus described my invention, what I claim is;

1. The combination with a tappet guide, tappet and push rod, of a casing carried by the guide and surrounding adjacent ends of the tappet and push rod and adapted to contain oil, a cover for the casing in spaced relation to the push rod and a resilient washer carried by the cover in engagement 70 with the push rod.

2. The combination with a tappet guide, tappet and push rod, of a casing carried by the guide and surrounding adjacent ends of the tappet and push rod and adapted to contain oil, a cover for the casing, a rigid washer within the cover engaging the end 75 of the casing, and a resilient washer between the cover and rigid washer.

3. In combination, a tappet, a push rod engaging the tappet, one of said members being pocketed to loosely receive the other and constitute a dash pot, and a reservoir 80 for a cushion liquid having communication at substantially its bottom with the open end of said dash pot thereby to supply liquid to the dash pot while any remains in the reservoir.

In witness whereof, I have hereunto set my hand.

JAMES R. TULLY.
